WINDOW LOCK

Abraham Kaufman and Harry Korman,

New York, N. Y.

Application July 2, 1943, Serial No. 493,245

3 Claims. (Cl. 292—251)

This invention relates to window locks.

An object of this invention is to provide a highly improved window lock of the character described which has parts interchangeable for size, and which is easy to assemble, and has no screw threaded openings other than the opening in a nut, thus reducing greatly the machining costs of the lock.

Another object of this invention is to provide a compact, strong and durable window lock of the character described which shall be relatively inexpensive to manufacture, easy to apply to a window, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an elevational, cross-sectional view of a window provided with a window lock embodying the invention;

Fig. 2 is a cross-sectional view taken on line 2—2 of Fig. 1;

Fig. 3 is a cross-sectional view taken on line 3—3 of Fig. 1; and

Fig. 4 is an exploded perspective view of various parts of the window lock.

Referring now in detail to the drawing, 10 designates a window provided with a window lock 11 embodying the invention. The window 10 may be of the double-hung sash type, and comprises a frame 12 in which there is slidably mounted a lower window sash 13 and an upper window sash 14. The window lock 11 is attached to the top portion 13a of sash 13, and has means to engage a portion 14a of the sash 14.

The lock 11 comprises a member 20 which may be made of metal, die-pressed and stamped into the shape shown in the drawing. As illustrated in the drawing, member 20 comprises a pair of co-planar wings or ears 21, each formed with an opening or aperture 22 to receive a fastening screw 23 screwed into the top of sash portion 13a. Extending from the ears 21 are upwardly and forwardly inclined walls 24 forming an inverted V-shaped portion. The walls 24 are slotted along parallel, longitudinal lines, as at 25, forming therebetween a strap 26 which is

pressed downwardly to form a V-shaped portion comprising downwardly and inwardly converging portions 27.

As shown in the drawing, a square nut 30 may be dropped onto strap 26 to rest between the portions 25a of walls 24 on opposite sides of the slits 25. The nut will thus be positioned with its sides at 45° to the horizontal and vertical, as illustrated in Fig. 3 of the drawing.

Screwed to the nut 30 is a screw threaded member 31 having a shank 32 engaging the threaded opening of said nut. The screw 31 has a looped handle 33 at one end of the shank 32. It will be noted that the shank 32 passes below the side portions 25a of member 20. The screw is thus prevented from moving upwardly off member 20.

At the forward end of screw 31 is a tip 35 on which is mounted a cup-shaped member 36 which is adapted to contact portion 14a of sash 14. The outer end of tip 35 is riveted, as at 37, to hold the cup 36 on said tip.

It will be noted that the size of the nut 30 and screw 31 may be varied as there is enough play beneath the strap portions 25a to accommodate various sized screws and nuts.

It will be further noted that the nut 30 contacts the inner edges of strap portions 25a and is thus held against side movement although there is sufficient clearance to accommodate nuts of various thicknesses.

Member 20 does not need to be formed with any screw threaded openings, and the only screw threaded part is the nut and screw. In assembling the parts the nut is first dropped into the slot in member 20, the screw 31 is then screwed through the nut, and the cup 36 is then applied to the tip 35 which is riveted to hold the cup in place.

It will also be noted that the strap 26 substantially forms a square with the strap portions 25a, and that a slot is formed in walls 24 to receive the square nut 30.

The V-shaped strap portion 26 does not extend below the plane of the underside of the apertured ears, so that member 20 may rest on top of portion 13a of the sash 13.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter

herein set forth or shown in the accompanying drawing is to be interpreted as illustrative and not in a limiting sense.

Having thus described our invention, we claim as new and desire to secure by Letters Patent:

1. A window lock comprising a member having a pair of apertured ears, and an inverted V-shaped part interconnecting said ears and comprising portions inclined upwardly and inwardly from said ears, said portions being formed with parallel slits, and the portions between the slits being pressed downwardly to form a V-shaped strap part comprising downwardly and inwardly inclined portions, and providing a slot in the inverted V-shaped part of said member, a nut within said slot and on said V-shaped strap part, and a screw screwed through the opening in the nut.
2. A window lock comprising a member made from a single piece of sheet metal, and having a

pair of co-planar, spaced, apertured portions, and a pair of upwardly and inwardly inclined walls extending from said apertured portions, said upwardly and inwardly inclined walls forming an inverted V and being slitted at its apex by a pair of parallel slits, the metal between said slits being depressed to form a V-shaped strap, a nut on said V-shaped strap, and a screw screwed through said nut.

3. A window lock comprising a member adapted to be attached to a window sash and formed with a pair of spaced slits, the portion of said member between said slits being depressed to form a slot, and a pair of parallel straps on opposite sides of said slot, a nut non-rotatably received and substantially fitting within said slot, and a screw screwed to said nut and extending beneath said pair of straps and above said depressed portion.
